UNITED STATES PATENT OFFICE.

AUSTIN FREDK. JACKSON, OF TAUNTON, MASSACHUSETTS, ASSIGNOR TO
REED & BARTON, OF SAME PLACE.

DESIGN FOR A SPOON OR FORK.

SPECIFICATION forming part of Design No. 15,517, dated November 4, 1884.

Application filed July 15, 1884. Term of patent 7 years.

To all whom it may concern:

Be it known that I, AUSTIN F. JACKSON, of Taunton, in the county of Bristol and State of Massachusetts, have invented and produced 5 a new and original Design for the Handles of Spoons, Forks, or Analogous Articles, of which the following is a specification, reference being had to the annexed drawings, forming part thereof.

10 Figures 1 and 2 are back views of a fork and spoon; and Figs. 3 and 4 are front views of the same, showing my new design.

A indicates the bowl of the spoon, and B the handle. The front surface of the handle 15 is provided with a raised figure, C, extending obliquely across the same from the bowl A to a point slightly distant from the outer end of the handle, and the ends of the said figure are convoluted, being curved in opposite directions. The figure C is made tapering toward the bowl A to a point near its inner end, and toward its outer end it branches off from a single stem, a, into a series of slightly-curved stems, b, which lie alongside each 20 other and terminate in successive order near the edge of the handle. On the inner portion of the handle, at one side of the figure C, is a raised wreath of leaves and flowers, D, extending from the inner convolution of figure 25 C to the bowl A, and on the outer portion of the handle, on the opposite side of figure C, is a wreath, E, extending along the longest stem, a, and terminating at a short distance from the outer end of the handle. At the outer

end of the handle is a smooth surface, F. The 35 under surface of the handle B is provided with a raised figure, G, consisting of a series of straight inwardly-tapering stems, c, arranged alongside each other within a bead, d, and extending from near the middle of the 40 handle to a point near its inner end, where they terminate in a single stem, c, or the body of the handle. The middle stem, c, is slightly longer than the others, which decrease in length toward the sides. At the extreme 45 outer end of the handle, on its under surface, is a cluster of leaves and flowers, H, and between the latter and the figure G is a smooth surface, I.

What I claim is—

- 50 1. The design for a spoon or fork handle, consisting of the figure C, shaped as described, having the wreaths D E on opposite sides of said figure, as shown and described.
2. The design for a spoon or fork handle, 55 consisting of the figure G and the cluster of leaves and flowers H, substantially as shown and described.
3. The design for a spoon or fork handle, consisting of a figure, C, arranged diagonally 60 or obliquely on the handle, and composed of curved parallel stems, with the stems longest on one side and decreasing in length toward the other side, as shown and described.

AUSTIN FREDK. JACKSON.
